UNITED STATES PATENT OFFICE.

WILLIAM HENRY CLEGG, OF BURNLEY, ENGLAND.

DEVICE FOR BINDING HOSE-PIPES TO METALLIC PIPES.

1,325,395.

Specification of Letters Patent.

Patented Dec. 16, 1919.

Application filed September 4, 1918. Serial No. 252,638.

To all whom it may concern:

Be it known that I, WILLIAM HENRY CLEGG, a subject of the King of Great Britain, residing at Burnley, in the county of 5 Lancaster and Kingdom of England, have invented certain new and useful Improvements in Devices for Binding Hose-Pipes to Metallic Pipes, of which the following is a specification.

10 This invention has for its object to provide a device by which a rubber hose pipe and a metallic pipe that is spigoted into it, can be bound or coupled together so as to provide a fluid tight connection.

15 My improved device comprises a flexible binding scrap, a loop through which the strap is passed twice to form a bight to go around the hose pipe, a second loop attached to one end of the strap through which the 20 strap is passed after passing through the first loop, such loops being arranged to provide a two-fold purchase to enable the strap to be drawn very tight, and a buckle or fastener attached to one end of the strap by 25 means of which the strap after being bound around the hose pipe can be held under tension.

In the accompanying drawings,

30 Figure 1 is a perspective view of my binding device;

Fig. 2 is a perspective view and Fig. 3 is a cross section showing my device applied to binding a hose pipe to a metallic pipe;

35 Fig. 4 is a cross section showing a slight modification.

In these figures, A is the metallic pipe, B the rubber hose pipe into which the metallic pipe is spigoted, and C a strap which is tightly wound around the rubber hose B to 40 bind it onto the metallic pipe with a uniform pressure so as to obtain a fluid tight joint. A strap made of strong woven tape is very suitable for the purpose, but other flexible binding material may be used. D is

45 a metallic rectangular loop through which the strap C is passed twice to form a bight E. In other words the strap C is doubled and the loop D slipped onto this doubled portion so as to form the bight E, such bight 50 being adapted to go around the hose pipe B at the place where it is to be bound to the metallic pipe A. The strap C has permanently fastened to it at one end, a second rectangular metallic loop F through which 55 the strap after passing through the loop D is also passed, such loops D and F being ar-

ranged to provide a two fold purchase to enable the strap to be drawn very tight around the hose pipe. G is a metallic buckle or fastener attached to the same end of the 60 strap C as the loop F is fastened to. This fastener or buckle may be of the type provided with the usual prongs and cross bar but any other suitable fastener may be employed. A convenient plan for fastening 65 the loop F and buckle G to the strap C, is by threading the end of the strap C through the frame of the buckle G and through the loop F, then bending back the said end and stitching it at H.

70 The bight E having been passed onto the hose pipe at the place where it is to be bound to the metallic one, the strap is drawn taut so as to pull the fixed loop F and the buckle G close up to the loop D and also tighten the 75 bight E around the hose pipe, the loop D providing the necessary mechanical purchase. The free end of the strap is now passed around the outside of the bight E from the loop D to the loop F through 80 which it is threaded or reeved (Figs. 2 and 3), (or over a pin K resting upon the loop F, Fig. 4) and then without slackening the tension, the strap C is passed back again 85 from the loop F to the buckle G through the space between the buckle bar and the prongs, the latter being caused to clench or engage the strap so that it cannot slip back whereby tension is maintained. The loop F also provides the necessary purchase, so 90 that a two fold purchase is obtained to bind the strap very tightly around the hose. If any loose end of the strap is left projecting beyond the buckle G this loose end is doubled or folded as shown at I and the doubled 95 portion held closely and compactly against the outer turn of the strap C by a clip such as J. This clip consists of a strip of flexible metal which is a good deal longer than the width of the strap. It is placed 100 transversely under the outer turn of the strap C and the ends bent over the folded portion I so as to clip and hold the same in place. The device provides an even binding pressure around the rubber pipe so that a 105 fluid tight joint is obtained, and can be applied to pipes of almost any size.

I declare that what I claim is:—

1. A device of the character described, comprising in combination a flexible binding 110 strap, a loop through which said strap is passed to form a bight to receive the hose

- pipe, a second loop attached to one end of said strap and through which the other end of the strap is passed, after passing through said first mentioned loop, said loops being arranged to provide a two-fold purchase to enable the strap to be drawn very tight, and fastening means attached to one end of the strap by means of which the strap after being wound around the hose pipe is held under tension.
2. A device of the character described, comprising in combination a flexible binding strap, a loop through which said strap is passed twice to form a bight to go around the hose pipe, a second loop attached to one end of the strap and through which the other end of the strap is passed after passing through said first mentioned loop; fastening means attached to one end of the strap by means of which said strap after being wound around the hose pipe is held under tension.
3. A device of the character described, comprising in combination a flexible binding strap, a loop permanently attached to one end of said strap, a buckle permanently attached to the same end of the strap, and a second loop through which a portion of said strap is passed to form a bight.

In witness whereof I have hereunto signed my name this 12th day of August, 1918, in the presence of two subscribing witnesses.

WILLIAM HENRY CLEGG.
